UNITED STATES PATENT OFFICE.

SAMSON P. MUNN, OF ST. LOUIS, MISSOURI, ASSIGNOR OF FIFTY-FIVE ONE-HUNDREDTHS
TO JUSTIN T. FLINT, OF ST. LOUIS, MISSOURI.

SMOKE-CONSUMER.

1,301,588.

Specification of Letters Patent. Patented Apr. 22, 1919.

Application filed August 27, 1917. Serial No. 188,262.

To all whom it may concern:

Be it known that I, SAMSON P. MUNN, a citizen of the United States, residing at the city of St. Louis, in the State of Missouri, **5** have invented certain new and useful Improvements in Smoke-Consumers, of which the following is a specification.

This invention relates to smoke-consumers, and has for its object the elimination of **10** objectionable features of certain devices of that character now on the market and the provision of new means for smoke prevention.

In the accompanying drawings forming part of this specification and in which like **15** numbers of reference denote like parts wherever they occur,

Figure 1 is a front elevation;

Fig. 2 is a side elevation, partly in section;

Fig. 3 is a front elevation (partly in section) on an enlarged scale of part of the **20** subject-matter of Fig. 1; and

Fig. 4 is an elevation of the same partly in section, the same being taken on the line **4-4** of Fig. 3, viewing in the arrow-indicated **25** direction.

The furnace 1, boiler 2, stack 3, ashpit 4, grate 5, and firebox 6 may be of any ordinary or desired construction.

Heretofore, the attempt has been made to **30** supply the fire with warmed smoke-containing air taken from the stack 3 by a fan, which fan, after drawing in such air forces the same into the firebox. This has been found very objectionable, because thereby **35** smoke and sulfur fumes are forced out into the furnace-room. The present invention obviates this difficulty by drawing in fresh air containing an abundance of oxygen by means of fan 7 through the inlet 8 and feeding the **40** same through the outlet-pipe sections 9 of pipe 10 over the grate 5, the outlet pipe-sections passing through the furnace wall. In actual practice, this has been found to cause instant cessation of emission of smoke from **45** the stack 3 while firing is taking place.

The horizontal pipe 10 disposed transversely of the furnace conducts air over the flame during firing and the vertical pipe 11 conducts air under the grate 5 during normal **50** operation. Pipe 11 leads from the fan 7 and the pipe 10 is tapped into the pipe 11.

Damper or valve 12 controls the direction of the passage of air into one or the other of the said pipes. A rock-shaft 25, rotatably **55** mounted at the confluence of the pipes 10 and

11, is secured to said valve, whereby movement of said shaft will move said valve to cut off passage through said pipe 10 and open passage through the pipe 11, or vice versa. One end of a lever 25' is secured to one end **60** of said rock-shaft 25, and one end of a link 13 is pivotally connected with said lever intermediate of the length thereof. The other end of said link has a hinged connection 14 with the upper end of a piston-rod 15 slidably mounted in bearings in a bracket 15' secured to the furnace wall. The piston-rod is connected with the piston 16 in cylinder 17, which is provided with escape ports 18, 19, and 20, and the quick air-intake valve 21. **70** The end of the lever 25' opposite that end which is connected with the rock-shaft 25 is provided with a handle 22. One end of a cable 24 is secured to said handle 22, the cable passing over a suitable pulley 24', and **75** carrying, at its other end, a weight 23. When the piston is forced downwardly at the time when damper 12 is shifted by means of handle 22 from its normal position of closing pipe 10 to the firing position of closing pipe 11, leaving pipe 10 open, air is forced out of ports 18 and 19, and air is forced out of port 20 when the piston 16 moves in the opposite direction, the weight **80** 23 at once beginning to exert a pull toward closing damper 12 against the retarding action of the air in cylinder 17 above piston 16. The ports 18 and 19 are larger relatively than port 20, and allow the quick depression of piston 16 and a rapid movement of the valve 12 to open passage through the pipe 10, while the escape of air through port 20 when weight 23 exerts its force on piston 16 through cable 24 and rods 13 and 15 is comparatively slow, thus causing a relatively **85** slow movement of the valve 12 and a relatively slow closing of passage through the pipe 10. Thus the feed of air through pipe 11 to underneath grate 5 can be instantaneously deflected to over the grate and flame through pipe 10, and the supply of extra oxygen thus furnished to stimulate combustion at the time of firing is gradually reduced and then shut off by the slow-closing operation of damper 12 by the action of weight 23 **90** on piston 16.

Having thus described this invention, I hereby reserve the benefit of all changes in form, arrangement, order, or use of parts, as it is evident that many minor changes may **110**

be made therein without departing from the spirit of this invention.

I claim:

1. In combination, a furnace including a fire box, grate and ash pit, a fan, a main pipe leading from the fan to the ash pit, a branch pipe connecting the main pipe and the fire box, a pivot adjacent the juncture of the main and branch pipes, a damper mounted on the pivot and adapted to be swung to either close the open end of the branch pipe leading from the main pipe, or to close the main pipe, an arm extending from the pivot, means including a weight connected to the outer end of the arm to normally operate the damper to close the branch pipe, and means connected to the arm for permitting of quick operation of the damper to close the main pipe and open the branch pipe to permit air from the fan to pass to the fire box, said means preventing the quick movement and permitting the slow movement of the damper to close the branch pipe under the influence of the weight and open the main pipe to permit air to pass from the fan to the ash pit.
2. In combination, a furnace including a fire box, grate and ash pit, a fan, a main pipe

leading from the fan to the ash pit, a branch pipe connecting the main pipe and the fire box, a pivot adjacent the juncture of the main and branch pipes, a damper mounted on the pivot and adapted to be swung to either close the open end of the branch pipe leading from the main pipe, or to close the main pipe, an arm extending from the pivot, a rod connected to the arm, a piston on the rod, a cylinder in which the piston operates, said cylinder having a small vent opening at its upper end and larger openings at the opposite end, and a valve in the upper end of the cylinder, whereby when the arm is moved down the damper quickly opens the branch pipe and closes the main pipe, the air being forced from the cylinder through the large openings below the piston, the weight acting to return the damper to open the main pipe and close the branch pipe, the air in the cylinder above the piston being forced through the small openings at the upper end of the cylinder thereby permitting the slow movement of the damper.

In testimony whereof I hereunto affix my signature.

SAMSON P. MUNN.
